UNITED STATES PATENT OFFICE.

RODERICK G. COLLINS, JR., OF NEW YORK, N. Y.

PNEUMATIC-DESPATCH APPARATUS.

1,108,136.

Specification of Letters Patent.

Patented Aug. 25, 1914.

Application filed April 16, 1913. Serial No. 761,584.

To all whom it may concern:

Be it known that I, RODERICK G. COLLINS, Jr., a citizen of the United States, residing at New York, in the county of New York and State of New York, have invented new and useful Improvements in Pneumatic-Despatch Apparatus, of which the following is a specification.

This invention relates to improvements in pneumatic despatch apparatus designed for the safe transportation of freely running carriers of large caliber for heavy traffic as distinguished from what are commonly known as store-service carriers, and particularly to systems embodying a single transmitting tube for the transportation of carriers in both directions and with which tube any desired number of branch tubes has communication, and in which system there is a central power station from which carriers may be despatched by blast and to which carriers may be transported by suction.

The invention has for its object to provide such a system with means controllable from the central station by which the traffic or transportation of carriers may be safely and expeditiously carried on.

The invention will be hereinafter described and the preferred embodiment illustrated in the accompanying drawings. That which is regarded as new is set forth in the claim appended to the description.

In the accompanying drawings,—Figure 1 is a general diagrammatic plan of a system embodying the invention. Fig. 2 is a detail of the valve controlling cylinders. Fig. 3 is a detail of the controlling valves for starting pressure.

In the said drawings, the reference numeral 1 designates the transmitting tube through which carriers containing goods or things to be transmitted are adapted to travel.

2 designates what, for convenience, I will term the central station or controlling terminal of the system.

3 designates the opposite terminal of the system, and 4 intermediate station terminals to and from which said carriers may be despatched. At the controlling terminal is arranged a fan or blower 5, both the suction and pressure sides of which 6 and 7 are in communication with the transmitting tube 1, so that suction or pressure may be the agency for the transportation of the carriers. The reference numeral 8 designates

one suitable type of valve mechanism for placing either the suction or pressure side of the blower in communication with the transmitting tube. The valve element 9 of the valve mechanism is connected by links 10 to valves that open and close at the suction and pressure sides of the fan to atmosphere; and the arrangement is such that when the valve 9 is in position to establish communication between the suction side of the blower and the transmitting tube 1, as shown in full lines in Fig. 1, the valve 10 closes the suction branch pipe from atmosphere and opens the valve 11 to atmosphere for exhaust of the blower. When the valve 9 is in position to place the pressure side of the blower in communication with the transmitting tube the valve 11 is closed to atmosphere and the valve 10 opened to afford air supply to the blower.

If it is desired to send articles or a carrier containing the same from the controlling terminal to the opposite terminal 3 of the system, the pressure side of the blower is placed in communication with the transmitting tube behind the goods or contained carrier, and the latter is forced through the tube to the opposite terminal. If it be desired to transport a carrier from said opposite terminal 3 to the controlling terminal 2, the suction end of the blower is placed in communication with the transmitting tube and by suction draws the carrier through the transmitting tube, as will be obvious.

The transmitting tube shown is a single tube through which, as hereinbefore explained, carriers may be sent in opposite directions of the system. At the control terminal, as well as at the opposite and the station terminals, the single transmitting tube is fashioned into two branches 1^a and 1^b, at the juncture of which branches with the tube 1 is a combined switch and air gate 1^c that may be manipulated to direct incoming carriers alternately or electively into either branch and close such branch behind the carrier against the influence either of the suction or blast of the blower. The said tube branches are provided with valves, shown conventionally and diagrammatically as rotary valves, 12, 13, which normally are closed so that the carrier passing thereinto and the combined switch and air gate closing the tube behind the carrier the latter comes to air cushion rest in the tube. The valves 12, 13, are each provided with a

crank arm 14 connected, respectively, to piston rods 15, the pistons of which move in cylinders, the opposite ends of which have communication with pneumatic pressure 5 from a pressure tank 16 by means of a conduit 17, 17^a, having appropriate branches communicating with the opposite ends of the cylinders as aforesaid.

18 designate valves associated with the 10 branches of the conduit so that pressure may be admitted at either side of the piston at will. After a carrier has come to rest in either of the tubes, as before explained, the valve associated with said tube is opened by 15 air pressure in the appropriate cylinder by manipulation of the corresponding valve 18 so that the carrier may pass from the tube to a delivery point. That the carrier may be so delivered, it is designed that an air blast 20 be introduced behind the carrier into the branch which, as before stated, has been closed to the transmitting tube. This is accomplished by placing said branches in communication with a pressure tank 19 by 25 means of a conduit 20 to both branches 1^a and 1^b arranged in which are suitable valves 21 shown in detail in Fig. 3 which valves are connected to and operable by the movement of the piston rod 15 as shown. The 30 pressure tanks 16, 19 are in communication with a pressure supply tank 22 by way of conduits supplied by suitable pressure reducing valves 23 and, in operation, it is designed that the pressure in the tank 16 which 35 operates the valve opening and closing pistons shall be of low pressure, as low pressure is sufficient to accomplish that function; and that the tank 19 which supplies the pressure to the tubes for ejecting the carriers there- 40 from shall be of medium pressure.

When it is desired to send carriers from the control terminal, the appropriate valve 12 or 13 is first opened by a proper manipulation of the associated valve to admit pressure to that side of the cylinder which 45 causes the piston rod to open the valve. The carrier is then pushed into the branch of the transmitting tube and the valve closed. For the purpose of sending the carrier through 50 the branch and into the transmitting tube in such position that it may be propelled through the tube by a blast of the blower, the medium pressure tank has communication with the tubes 1^a, 1^b at points contiguous 55 to the valves 12, 13, which communication is controllable by manually operable valves 25, 26, to admit a blast behind the carrier to convey it to and past the point where the blower has communication with 60 the transmitting tube, so that it will be subject to the blast of the blower. The pivot of the combined switch and air gate 1^c is connected to the piston of an air cylinder 30, and this is so with the corresponding 65 switches and air gates of the other terminal

hereinbefore referred to, and a manually controlled valve 31 is provided for the admission of pressure to the opposite ends of the cylinder to shift the switch and air gate to either of its positions. Thus the operator 70 at the control station may in receiving carriers send them alternately into one or other of the branches, as he may desire. In sending the carriers from the control station he may do likewise; that is to say, he may 75 deposit the carrier in either of the branches 1^a or 1^b and shift the switch and air gate accordingly.

During the sending operation the switch and air gate 1^c will be so positioned as to 80 close the particular branch 1^a or 1^b through which the operator may wish to send the carrier, during the period when the carrier admission valve 12 or 13 for the particular branch in use is open, in order that this 85 switch and air gate will form an air lock and prevent power from the blower 5 passing to the branch 1^a or 1^b in use. This is desirable not only because it would be 90 troublesome to insert the carriers if the branch were open and subjected to the suction or pressure from the blower 5, but there would be also a loss of power when the entrance valve 12 or 13 of the branches were 95 opened, and a consequent reduction of pressure or suction throughout the entire system which would result in cutting down the speed of the carriers throughout the system. When the carriers have been inserted, and the admission valve in the branch in 100 use is again closed, the switch and air gate 1^c will be thrown open by the operator to give free passage for ejecting the carrier from the branch to the main line.

At the opposite terminal, and at the intermediate station terminal, the switch and air gate may be provided with very similar shifting mechanism. As shown in Fig. 1 the air gate is provided with the operating arm 32 controlled from the cylinder 33, 110 which is connected by branch passages with the pressure tank 34 which is supplied through the regulating valve from the high pressure tank 35 fed from a suitable air compressor 36, conventionally shown.

The system of my invention embodies a central or control station, an opposite terminal or station, and at least one branch or intermediate station having communication with the transmitting-tube. I have so shown it as a simple embodiment of the inventive idea. It is obvious that there may be more than one intermediate or branch station and the accessories thereof hereinafter described. I provide combined air-gates and switches at the juncture of the intermediate station tubes with the main transmitting tube, and in order that these tube air-gate-switches may be controlled from the main station I provide means, preferably electrical, where- 115 120 125 130

by the operator at the main station may control the position of the tube switches. It will be observed, of course, that the power mechanism is also located at the central or control station so that the operative at that station has it within his control to utilize either blast or suction, and he has it within his control to send from the central station carriers to the opposite terminal or to any intermediate station, and he also has it within his control to place the said opposite terminal or any intermediate station in communication with the central or control station to enable carriers to be transported from said opposite terminal or an intermediate station. According to my invention, collision of carriers within the system and possible wreckage and damage to the system by reason of such collision is provided against, because of the interposition, at the juncture of the branch or intermediate station tubes with the main tube, of the combined air-gate-and-switch under the control of the operative at the central station. It is obvious that when any branch station is placed in communication with the main transmitting-tube by the operative at the central station the suction is cut off from all other branch stations and from the opposite terminal station.

In Fig. 1, 37 indicates the tube air-gate-switch which is like the combined switch and air-gate 1^e hereinbefore described, that is to say it serves not only to direct the movement of the carriers but as an air tight closure or gate. I have shown herein the combined switches and air-gates 1^e and 37 merely schematically, as the same and the details are disclosed in my co-pending application filed March 29, 1913, Serial No. 757,523, which is provided with an operating arm coupled to the piston of the pressure cylinder 38, similar to the pneumatic power mechanism heretofore described, this pressure cylinder coupling with a branched pressure passage coming from any suitable source of pressure supply, as the tank 39, which is fed from the air compressor 36 and

high pressure tank 35 through a suitable reducer and feed pipe. The branched passages going to the pressure cylinder 38 are controlled by a valve mechanism 40, similar to that shown in Fig. 3, so that either of the tube passages may be opened or closed at will. To operate the valve there are, preferably, provided two coils 41 adapted to move the solenoid core 42 in one direction or the other, dependent on which of the solenoid coils 41 is energized. The coils 41 are in separate circuits, diagrammatically shown, running to the switch board 43 preferably located near the main station or terminal 2, so that the operator at the main station by energizing one or the other of the coils may move the solenoid coil 41 to actuate the valve 40, which is operatively connected with the solenoid core.

Having thus described my invention, what I claim is:—

In pneumatic - despatch - apparatus, the combination with a transmitting-tube, a control station communicating therewith, an opposite terminal station and a branch station also communicating therewith, a combined air-and-gate-switch at the point of communication of said branch station with said tube, means for operating said air-and-gate-switch from the control station to close communication between the control station and the opposite terminal station and stop the flow of air therethrough and establish operative communication between said control station and the branch station, or vice versa, and a combined suction and pressure pneumatic power mechanism located at said control station and means for selectively subjecting said tube to the suction or pressure thereof.

In testimony whereof I have hereunto set my hand in presence of two subscribing witnesses.
